Primary Examiner — Michelle E. Wilson*(74) Attorney, Agent, or Firm* — Price Heneveld LLP(57) **CLAIM**

The ornamental design for a manual laundry device, as shown and described.

DESCRIPTION

FIG. 1 is a front perspective view of a manual laundry device according to our design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

Broken lines depicting portions of the article form no part of the claimed design.

Dash-dot lines adjacent un-shaded areas represent bounds of the claimed design and form no part of the claimed design themselves.
